(57) CLAIM

An ornamental design for a drainage track, as shown and described.

DESCRIPTION

FIG. 1 is a perspective view of the drainage track to which the design has been applied;

FIG. 2 is a top view of the drainage track of FIG. 1;

FIG. 3 is a front view of the drainage track of FIG. 1;

FIG. 4 is a rear view of the drainage track of FIG. 1;

FIG. 5 is a bottom view of the drainage track of FIG. 1;

FIG. 6 is a right side view of the drainage track of FIG. 1; and,

FIG. 7 is a left side view of the drainage track of FIG. 1.

The drainage track is broken in the center indicating indefinite length.
